UNITED STATES PATENT OFFICE.

CHARLES LEONARD ARNOLD AND CHARLES REGINALD BELLING, OF ENFIELD,
ENGLAND.

ELECTRIC SWITCH.

Application filed August 31, 1921. Serial No. 497,162.

To all whom it may concern:

Be it known that we, CHARLES LEONARD ARNOLD, a subject of the King of Great Britain and Ireland, and resident of Enfield, in the county of Middlesex, England, and CHARLES REGINALD BELLING, a subject of the King of Great Britain and Ireland, and resident of Enfield, in the county of Middlesex, England, have invented new and useful Improvements in Electric Switches, of which the following is a specification.

This invention has relation to electric switches and it has for its object to provide improvements by which certain advantages shall be obtained.

An electric switch, in accordance with this invention, comprises a pivotally mounted contact carrying member, a pivotally mounted actuating member and a pivotally mounted third member which, on movement of the actuating member, is engaged thereby, moved therewith, and caused to engage and impart movement to the contact carrying member.

In order that the invention, the nature of which has been set forth, may be clearly understood and readily be put into practice, reference will now be made to the accompanying sheet of drawings, on which:

Fig. 1 is a sectional elevational view, and Fig. 2 a sectional plan view of one construction of switch;

Fig. 3 is a sectional elevational view, with the switch parts in the open position;

Fig. 4 an end elevational view; Fig. 5 a sectional plan view; and

Fig. 6 a sectional elevational view, with the switch parts in the closed position, of a modified construction of switch.

1 is a framework of any suitable design and construction in which the movable parts of the electric switch are mounted and which also serves, in the two constructions illustrated, to carry the fixed contacts 2 of the switch. The framework 1 also serves for the mounting of the switch.

3 is a movable member carrying the contact 4 which co-operates with the fixed contacts 2. The member 3 is of U-shape in plan, and is pivotally mounted at its open end on pins 5 carried by the side walls of the framework 1. The contact 4 is insulatingly mounted on the closed end of the member 3.

6 is another movable member, also of

U-shape in plan view and pivotally mounted at its open end on the pins 5 and between the arms of the member 3. 7 is a handle mounted on the closed end of the member 6. 8 is a spring connected at one end with a pin 9 mounted in the side arms of the member 3 and at the other end with a pin 10 mounted in the side arms of the member 6. 11, 12 (Figs. 1 and 2) are two curved plates. The plate 11 is pivotally mounted on a pin 13 carried by one of the side walls of the framework 1 and disposed towards the right hand upper corner thereof. The plate 12 is pivotally mounted on a pin 14 carried by the other of the side walls of the framework 1 and disposed towards the right hand lower corner thereof. The plates 11, 12 are of different shape. The plate 11 carries two lugs or projections 15, 16 of which one, 15, extends above one side arm of the member 3 and the other, 16, below one side arm of the member 6. The plate 12 similarly has two lugs or projections 17, 18, of which the lug 17 extends below one side arm of the member 3 and the lug 18 above one side arm of the member 6.

The parts are shown in the open position of the switch. When the handle 7 is pressed, the member 6 is caused to turn about its pivots 5 and to contact with the lug 16. The pressure on the lug 16 causes the plate 11 to turn about its pivot 13 and the other lug 15 to contact with and press on the member 3, which, as a consequence, is constrained to move about its pivots 5 and move the contact 4 into engagement with the contacts 2. During and by the movements of the members 3, 6, the spring 8 is stressed and when the members have been moved to a position in which they are just past the straight line the spring 8 tends to move to its retracted position. The retractile movement of the spring 8 causes the member 3 to move in advance of the plate 11 and effect a quick make of the circuit. When the handle 7 is raised, the plate member 3 is moved about its pivots 5 through the plate 12, the lug 18 being acted on by one side arm of the member 6 and the lug 17 contacting with and pressing on the member 3. The opening movement of the member 3 is completed quickly by the spring 8.

The switch illustrated and described can be operated without a spring 8, but when the spring is omitted, or becomes inoper-

ative through breakage, a quick make and break is not obtained.

In the construction of switch illustrated in Figs. 3 to 6 inclusive, there is substituted for the plates 11, 12 a single plate 20 and pivotally mounted on a pin 25 carried by one of the side walls of the framework 1 and having four lugs or projections 21, 22, 23, 24. The lugs 21, 23 which are disposed oppositely come, respectively, above and below the member 3 and the lugs 22, 24 which are also disposed oppositely, come above and below, respectively, the member 6. It may, in some instances, be found desirable to duplicate the plate 20 and lugs 21, 22, 23, 24, the second plate then being mounted directly opposite on the other side wall of the framework 1.

What we claim is:

20. 1. An electric switch comprising a pivotally mounted contact carrying member, a pivotally mounted actuating member, a spring attached at its ends to said members, and a pivotally mounted third member having lugs projecting on opposite sides of, and into the paths of movement of, said members to transmit movement from the actuating member to the contact carrying member until the spring becomes operative, said third member being made in two parts, of which one is operative on the opening movement and the other on the closing movement of the switch.
25. 2. An electric switch comprising a pivotally mounted contact carrying member, a pivotally mounted actuating member, a spring attached at its ends to said members, and a pivotally mounted third member comprising two pivotally mounted plates, each having two lugs projecting into the paths of movement of the actuating and contact carrying members, one plate and lugs thereon functioning during the opening movement of the switch and the other plate and lugs during the closing movement of the switch.
30. 3. An electric switch comprising a pivotally mounted contact carrying member and a pivotally mounted actuating member both of U-shape in plan view, a spring attached at its ends to said members and a third

member comprising two curved plates each having two lugs thereon extending on opposite sides of the contact carrying member and actuating member, said plates being pivotally mounted on opposite sides of the contact carrying and actuating members and in different planes.

4. An electric switch comprising a pivotally mounted contact carrying member, a pivotally mounted actuating member, a spring attached at its ends to said members, and a pivotally mounted third member having four lugs projecting therefrom and disposed in pairs, the lugs of one pair being operative during opening of the switch and co-operating with the opposite sides of the actuating member and the contact carrying member and the lugs of the other pair being operative during closing of the switch and co-operating also with opposite sides of the actuating member and the contact carrying member.

5. An electric switch comprising a support, a switch plate pivoted therein, a switch lever pivoted in said support adjacent the pivot of the switch plate the switch plate and the lever extending in opposite directions from their pivots, a coil spring connecting the switch plate to said lever and arranged to pass across the pivotal points of said two parts, rigid stops for the switch plate in its "on" and "off" positions, contact arms carried by the switch plate, and a pair of kick-off levers pivoted in the support on opposite sides of the switch lever and adapted to be engaged and moved by the switch lever to swing the switch plate on its pivot.

6. An electric switch comprising a support, a switch plate pivoted therein, a switch lever pivoted therein, a coil spring connected to the lever and to the switch plate arranged to pass across the pivotal points of said two parts, and a pair of kick-off levers cooperating with the switch lever to swing the switch plate on its pivot.

Dated this seventeenth day of August, 1921.

CHARLES LEONARD ARNOLD.
CHARLES REGINALD BELLING.
